UNITED STATES PATENT OFFICE.

WALTER M. TIETZ, OF NEWARK, NEW JERSEY.

RAZOR HONE AND STROP.

Application filed April 27, 1925. Serial No. 26,098.

This invention relates more particularly to a class of razor sharpening devices.

My invention has for its object primarily to provide a device designed to be employed especially for sharpening razor blades, and which is of a form combining a honing stone and strop for enabling the blades to be whetted and subsequently stropped to a smooth cutting edge by using the single device instead of being required to employ these classes of separated sharpening devices which as ordinarily made are often inconvenient for use as well as being of a form for enabling the stone or strop when damaged to be replenished. The invention consists essentially of a stone having a face for whetting a razor, and in spaced relation to the opposite part of the sharpening face of the stone is a flexible strap element for stropping the blade subsequent to being whetted on the stone.

Other objects of the invention are to provide on the stone opposite its sharpening face spaced flanges for supporting the strap element; to provide clips for detachably fastening the ends of the strap element inlapping arrangement on the flanges; and to provide a razor hone and strop of a simple, efficient and durable construction which may be made in appropriate sizes and shapes.

With these and other objects in view, the invention will be hereinafter more fully described with reference to the accompanying drawing forming a part of this specification in which similar characters of reference indicate corresponding parts in all the views, and will then be pointed out in the claims at the end of the description.

In the drawing, Figure 1 is a perspective view of one form of razor hone and strop embodying my invention.

Fig. 2 is a sectional view taken lengthwise through the device on the line 2—2 of Fig. 1.

Fig. 3 is a perspective view of one of the clips used in the device, and

Fig. 4 is a side elevation, partly broken away, of the clip.

The device has a holding member 10 which may be formed of a class of natural stone adapted for sharpening razor blades, though I prefer to make the honing member of a well known composition stone having as its principal ingredient finely powdered emery which is freed of grit. The honing member or stone 10 has a body 11 which is preferably of a relatively flat substantially rec-

tangular shape for permitting its face, as 12, to be used for whetting a razor blade when dulled. Protruding angularly from the end parts of the opposite face, as 13, of the body 11 are two spaced flanges, as 14, 15, and these flanges are of partly square shapes extending across the entire width of the body 11. The flanges 14, 15 are preferably made integral with the body 11 of the composition stone which is molded and compressed according to the commonly used process.

Overlapping the free ends of the flanges 14, 15 and extending across the space therebetween in spaced relation to the face 13 of the body 11 is a strap element 16 of leather, canvas or other material suitable for stropping a razor blade to an even keen cutting edge. The strap or stropping element 16 is of a width corresponding to the lengths of the flanges, and the strap element is of a length so that its end portions, as 17, 17^a, extend over the outer side faces of the flanges to the ends of the body 11.

The strap element 16 is removably attached to the honing stone 10 by means of fastening devices or clips, as 18, 19. The clips 18, 19 are preferably of similar formations, and these clips may be of any suitable types, though the form of each clip illustrated has a body 20 of substantially the shape of an inverted U to provide two spaced arms or leg members 21, 22 and a bridging or spanning member 23. The clips are made of pliable sheet spring metal of relative thickness, and both clips are of lengths similar to the lengths of the flanges 14, 15 of the honing stone 10. The arm member 21 of the body 20 of each of the clips is preferably wider than the arm member 22 of the clip, and the arm member 22 of each clip is inwardly curved lengthwise of its free end portion, as 24. The space between the arm members 21, 22 of each of the clips is somewhat less than the thicknesses of the flanges 14, 15 of the honing stone 10 for allowing the clips to be removably sprung in straddle arrangement over the flanges of the stone. The spanning member 23 of each of the clips is arched or convexly curved, as at 25, from end to end, and the end of the arm member 21 of each of the clips opposite to the curved spanning member is outwardly bent to provide an approximately hook shaped member or catch 26. The strap element 16 is fastened to the clips 18, 19 by the

110

end portions of the strap element being disposed in lapping position over the spanning members 23 of the clips, and the free ends of the strap element are disposed in the hook members 26 of the clips. The outer walls or arms of the hook members are then bent toward the other walls of the hook members for tightly clamping the parts of the strap element in the hook members to securely fasten the clips and the strap element together.

The strap element 16 is removably mounted on the honing stone 10 by the clip members 18, 19 being removably sprung in straddle positions upon the flanges 14, 15 of the honing stone with the arms 22 of the clips engaging the inner faces of the flanges and with the arms 21 engaging the outer faces of the flanges. The tension of the arms 21 of the spring clips is such that the clips with the strap element will be firmly held to the flanges of the stone, and the arched spanning members 23 of the clips will serve to transversely curve, as at 27, 28, the strap element for preventing its lengthwise edges from tending to curl upwardly from the stropping face of the strap element since the curled edges of the ordinary razor straps frequently interfere with proper sharpening of the razor blades. The device as thus formed may be made in relatively small sizes for being conveniently held in one hand of a person for use, and when a razor blade is very dull it may be readily whetted on the sharpening face 12 of the stone, after which the blade may be stropped on the strap element 16 to a keen smooth cutting edge.

In the foregoing description, I have embodied the preferred form of my invention, but I do not wish to be understood as lim-

iting myself thereto, as I am aware that modifications may be made therein without departing from the principle or sacrificing any of the advantages of this invention, therefore, I reserve to myself the right to make such changes as fairly falls within the scope thereof.

Having thus described my invention, I claim as new and desire to secure by Letters Patent:—

1. A razor hone and strop, comprising a relatively flat substantially rectangular honing stone having spaced stone flanges protruding from one of its faces, a honing strap disposed upon the free edges of the flanges and extending across the space therebetween in spaced relation to the stone, and means under the end portions of the strap removably fastening it to the flanges and transversely curving the central portion of the strap between its lengthwise edges away from the stone.

2. A razor hone and strop, comprising a relatively flat substantially rectangular stone having spaced stone flanges protruding from one of its faces, a honing strap disposed upon the free edges of the flanges and extending across the space therebetween in spaced relation to the stone, and two clips each substantially U-shaped in cross section and having its bridging member convexly curved lengthwise, said clips being removably attached to the ends of the honing strap with the adjacent parts of the strap lapping upon the curved bridging members of the clips and the clips straddling and detachably clamping the flanges of the stone.

This specification signed this 25th day of April, A. D. 1925.

WALTER M. TIETZ.
